UNITED STATES PATENT OFFICE.

EMERY E. CLARK, OF TOPEKA, KANSAS.

ROTARY AMUSEMENT DEVICE.

Application filed March 26, 1927. Serial No. 178,673.

My invention relates to a rotary amusement device.

The chief object of my invention is to provide a power actuating means which 5 functions through the law of gravitation.

A further object of my invention is to provide a merry-go-round type of machine that will accommodate a number of occupants while only one occupant is necessary 10 to manipulate the driving mechanism.

A still further object of my invention is to provide a device of the kind herein set forth that is portable and adaptable for municipal play grounds, parks, private 15 homes, etc.

A still further object of my invention is to provide a rotary amusement device that is inexpensive, easily transported and operative by one occupant.

20 A still further object of my invention is to provide a rotary amusement device eliminating the use of rotatable power actuating shaft, cog wheels and the like, whereby the mechanism is rendered practically noiseless.

25 These and other objects will hereinafter be more fully explained.

Referring to the drawings:

Fig. 1 is a plan view, parts removed for convenience of illustration.

30 Fig. 2 is an elevation of the mechanism.

Fig. 3 is a sectional view of the diametrical axis.

Fig. 4 is an enlarged detailed elevation of the pedals and cable engaging means, parts 35 removed for convenience of illustration.

Fig. 5 is a perspective diagrammatical layout of the power actuating means, the levers being separated on the center post for convenience of illustration.

40 Fig. 6 is an enlarged sectional detailed view taken along the diametrical axis of the center post.

Fig. 7 is an enlarged plan view of the lever ratchet mechanism.

45 Fig. 8 is a front view of one of the seats.

Fig. 9 is a side view of Fig. 8.

In the drawings, there is shown a center post 1 vertically supported on a base consisting of a plurality of radially disposed 50 members 2, the said post extending through the intersections of said members and having a pin 3 diametrically positioned and outwardly extending, the ends of which engage in slots extending upward from the bottom as shown by dotted lines A in Fig.

6. By this arrangement the post is rigidly supported against rotation and as a means to prevent the post from downward movement I have placed a plate 4 on which the post will rest, the said plate being rigidly 60 attached to the base by means of screws or otherwise.

The horizontal platform herein disclosed is preferably polygonal consisting of arranged parts as follows:

Horizontally positioned and rotatably engaging on said post is a platform 5 having radial joints as at 6 by which means the triangular sections are removable and have their bearings on radially positioned 70 beams 7.

Centrally positioned in the platform is a metal disc member 8 functioning as means to which the beams may be rigidly attached, the said plate having a centrally positioned 75 aperture to engage rotatably on the post functioning as a bearing. As a means to centrally support the beams from downward deflection I have provided a collar 9 which is rigidly attached to the post on which a centrally positioned block 10 will engage, the said block being of equal thickness to the beams and rigidly attached to the disc against which the inner ends of the beams snugly engage.

80 Rotatably positioned on the post and having its bearing on the base members is a block 11 functioning as a thrust member for the inner ends of radial brace members 12, the said members angling upward and 90 connecting firmly to or near the outer ends of the beam 7 and rigidly attached thereto as a peripheral supporting means for the platform. The lower or inner ends of the brace members are supported to engagement 95 with the block 11 by means of Z-shaped irons 12' having the ends thereof firmly attached by means of bolts 13.

As an intermediate bearing between the block 11 and the base member is a pair of 100 concaved washer members 14 which are attached respectively to the said block and base so that the convex sides rotatably engage for easy rotation of the platform.

In close proximity but spaced from the 105 edges of the platform sections is a seat carrying strips 15 the ends of which are rigidly attached to the beam members by metal hangers 16. Paralleling said strips and carried by the outer ends of the beams 110

is a second seat carrying member 17 rigidly attached to said beams by means of corner irons 18.

Positioned on the strips and carried thereby are seats 19, the said seats having metal strips 20 vertically positioned and attached to the insides thereof and extending downward to engage on the inside of the strips 15 by which means the seats are retained in proper position and prevented from sliding outward by centrifugal force or otherwise. To prevent displacement by moving inward, the inside of the seat is in contact with the edge of the platform section as shown in Fig. 8. By this manner of construction the seats will slide longitudinally on the strips as comfortable adjusting means for the occupant.

Pendently supported from the strips are steps 21 by means of straps 22, the said straps having a hook 23 on the upper end thereof to engage with the strips, the lower ends firmly connected to the steps, the said step being a convenient means for mounting the seat and also a foot rest for the occupant.

A similar step carried by the strips 17 exclusively is positioned near the operator as shown at 24 in Fig. 1. It will be understood that the pendent support for the steps will slidably engage on their respective bearings to accommodate for the position of the seats, except the last said step 24 which is rigid.

Supported in a horizontal position by means of the rigidly fixed center vertical post 1 are two ratchet levers 25 and 26. The said post serves as an axis upon which the body of the machine revolves by alternately applying a weight to either of two pedals 27 and 28 which are pendently carried by hangers 28', the said pedals being connected by cables to the outer ends of two ratchet levers horizontally positioned on said center vertical post, said cables passing under or over a series of small sheaves positioned near the outer edge of the frame of the machine so that the directional pull of said cables, will always be at one side of the center, thereby creating a leverage causing the machine to revolve when a weight is applied to either pedal, there being two pedals and two levers.

The pedals are connected to the ratchet levers by means of four cables, two of which are fastened to each pedal, the two cables in each instance being fastened to the lever arms, one to the front end of one lever arm and the other to the rear end of the other lever arm thereby causing a scissor movement of said arms when either pedal is forced down simultaneously with the upward movement of the other pedal. The said levers extend in opposite directions an equal distance from the center of the post, a pull 65 on one end of one of the levers causing the

load to advance while a pull on the opposite end of the other lever will advance the last said lever to a position for a repeated pull. The lever arms functioning in this manner in conjunction with the upward and downward movement of the pedals produce a continuous rotation of the mechanism in one direction.

I will now describe in detail the parts and their operative relation to each other co-acting for the said continuous rotation in one direction.

Referring specifically to the ratchet mechanism, attention is directed to Figs. 6 and 7 in which is shown ratchet gears 29 rigidly attached to the center post. Rotatably positioned thereon are levers 25 and 26. The said levers have apertures centrally positioned and with clearance sufficient to rotate without contacting the teeth of the gears.

Positioned in the side of the aperture is a pawl 29' tensioned by a spring 29", said pawl rockably seated and retained in such a way that the free edge thereof will engage with the teeth functioning as a ratchet. As a retaining means for the proper operative position of the levers relative to the ratchet gear, I have provided discs 30, to snugly engage on the ends of the ratchet gear, and peripherally in the aperture.

Positioned on the outside of the discs, and firmly attached to the levers, are plates 31, functioning as retaining means for the discs, the lower one of said plates, functions as a bearing for the levers on their respective collars 32 and 33. Between the lever arms the collar 33 is a separating member on which the upper lever will reciprocatingly engage, and likewise the other lever arm on collar 32.

Positioned at one corner of the platform is a sheave supporting member consisting of two plates 34 and 35. The said plates are supported by means of a frame 36 as shown in Fig. 4. The said frame is rigidly attached to strips 15 and 17. The top of the frame is anchored by a member 37 which is firmly attached to plate 34 and to an arch bar 38, the said bars being carried by said strips and braced at their lower ends by means of a diagonally positioned member 39. The arch bar extends across at its lower extremity functioning as a stop for the pedals in their extreme downward movement.

On the under side of the top plate 34 are trunnioned two sheaves 40 and 40', and on the top of the lower plate are two sheaves 41 and 41'. On the under side of said lower plate are two sheaves 42 and 42', the said sheaves functioning as bearings on which the cables heretofore described will engage as follows, reference being had to Fig. 5:

To the free end of pedal 27 are attached the ends of two cables B and B', the said cables engaging on the upper sheave 40 and

extending downward dividing so that cable B' will engage on sheave 41, and laterally extend to lever 25 connecting to the end as at B''. Cable B extends around sheave 42 and laterally extends to lever 26 connecting to the end thereof as at B'''.

It is now readily seen that by the downward movement of pedal 27 the mechanism will rotate in direction of the arrow as shown in Fig. 1, by reason of the ratchet in lever 25 stationarily supporting said lever and lever 26 is simultaneously rotated on the post to a position for a repeated tension by the downward movement of pedal 28 functioning as follows:

To the free end of said pedal are rigidly attached two cables C and C', the said cables extending upward engaging on sheave 40' and downward dividing so that one cable will engage on sheave 41' and laterally extending to and connecting with the end of lever 26 as at C'', the other cable engaging on sheave 42' and laterally extending and connecting to the end of lever 25 as at C'''.

This adjustment is ready for a further rotation through the medium of lever 26 and simultaneously the lever 25 is advanced for repeated tension. Therefore by the reciprocation of the pedals the mechanism is continuously rotated in one direction, it being understood that a similar pawl and ratchet is centrally positioned in the last said lever as described for the first lever.

Attention is further directed to a tension adjusting means for the cables consisting of turn buckles 43 positioned similar to that shown in Fig. 5.

Such modifications may be employed as lie within the scope of the appended claims.

Having thus described my invention, what I claim as new and desire to secure by Letters Patent is:

1. In combination, a rotary amusement device having a base supporting member, a vertical center post rigidly attached to said base and on which the device rotates, a pair of ratchet gears rigidly attached to the post, a lever centrally and rotatably positioned on each of said gears, a pawl in the levers to engage with the teeth of said gears so that both levers will rotate in the same direction, a pair of pedals peripherally positioned and hingedly connected to said device, a frame vertically positioned on said device in working relation to the free ends of the pedals, a plurality of sheaves carried by the frame, a pair of cables connected to the free ends of each of the pedals, said cables engaging on the sheaves, the opposite ends of the cables separately engaging with one end of each of the levers for alternately rocking thereof to rigid engagement with the post by the reciprocating movement of the pedals for the continuous rotation of the said device in one direction.

2. In a rotary amusement device, a mechanism of the kind described, a base supporting means, a vertically positioned post rigidly connected to the base, a structure to rotatably engage on said post, a pair of 70 pedals peripherally positioned on the rotatable structure, a pair of ratchet gears rigidly attached to the post in close proximity to each other, a lever centrally positioned longitudinally and rotatably engaging on each of said gears, pawls carried by said levers to engage with said ratchet gear so that the rotation of both will be in the same direction, a cable attached to one end of one of the levers, and a cable attached 80 to the opposite end of the other lever, both of said cables engaging on sheaves and connecting to one of said pedals, a second pair of cables connecting to the opposite ends of said levers engaging on other sheaves and connecting with the other pedal so that by the reciprocation of said pedals the said levers are rigidly engaged by the ratchets on the center post alternately for the continuous rotation of the mechanism in one 90 direction.

3. In a rotary amusement device, a device of the kind described having radially extending base members and a vertically positioned post at the intersection of said base members, a polygonal frame rotatably engaging on said post and carried by the base members, a sectional platform carried by the frame, parallel strips carried by the frame and spaced from their respective sections of the platform, seats positioned between the strips, said seats slidably engaging therein for conveniently locating the same, a pair of pedals pendently carried by the frame, pair of levers horizontally carried by the post so 100 that the ends extends in opposite directions an equal distance therefrom, a ratchet means for each of the levers so that each will rotate in the same direction, means to rotate the frame by the cables' tension on the levers 105 alternately and means to position the levers alternately during the rotation of said frame, substantially as shown and described.

4. In a rotary amusement device, a base supporting member having a center post vertically positioned and rigidly attached thereto, a horizontally disposed platform having supporting beams radially positioned, diagonally positioned brace members to engage with the beam members and having their lower ends trunnioned on the center post, said members revolving on the center post, a pair of ratchet gears rigidly attached to the post intermediate the beam and brace members, strips connected to the beams adjacent the edges of the platform, other strips carried by the outer ends of the beams and parallel with the first said strips, seats carried by said strips, steps pendently carried by said strips, a pair of pedals pendently 120 125 130

supported by one pair of said strips, a seat for the occupant operating the pedals, a frame having a top plate and a lower plate as supporting means for sheaves, the top plate having two sheaves to carry one pair of the cables respectively, the lower plate having two sheaves on the top and two on the under side, one cable to engage on each and extend longitudinally thereof, arms having apertures centrally positioned therethrough, a pawl peripherally positioned and ratchetly engaging in the aperture of each thereof, the said arms rotatably engaging on the ratchet gears, a pair of cables connecting to the free end of each of the pedals and ex-

tending over the sheaves on the top plate and from thence to be carried separately by the four sheaves on the lower plate so that the horizontally positioned portion will connect with both ends of the levers in such a way 20 that the downward movement of the pedals alternately will tension on one oppositely positioned end of both levers for a scissor movement. the said levers alternately engaging with their respective ratchet gears 25 causing the rotation of the said revolvable mounted members in one direction, all as, and for the purpose described.

In testimony whereof I affix my signature.
EMERY E. CLARK.
